UNITED STATES PATENT OFFICE.

EUGENE H. TAYLOR, OF LYNN, ASSIGNOR TO THE ROSS HEEL COMPANY, OF EASTON, AND ELBRIDGE S. MANSILL AND GEORGE O. TARBOX, OF LYNN, MASSACHUSETTS.

HEEL-STIFFENING MACHINE.

SPECIFICATION forming part of Letters Patent No. 392,975, dated November 13, 1888.

Application filed January 16, 1888. Serial No. 260,881. (No model.)

To all whom it may concern:

Be it known that I, EUGENE H. TAYLOR, of Lynn, in the county of Essex and State of Massachusetts, have invented certain new and useful Improvements in Machines for Forming Heel-Stiffeners; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to improvements in machines for forming heel-stiffeners for boots and shoes, and particularly to those parts of such machines as are immediately concerned in forming or molding the stiffener from the blank of leather.

The general purposes of this invention are, first, to turn the flanged part, crimp it, and then render it smooth and permanent by pressure, and, second, to press and polish the forward parts or sides of the stiffeners.

In the accompanying drawings, Figure 1 is a front elevation of my machine. Fig. 2 is a plan of the mold, bed-plate, former-crimper, and sliding plate. Fig. 3 is a side sectional elevation showing sliding cross-head, toggles, toggle-joints, mold, former-crimper, and finishing-crimper; and Fig. 4 is a bottom plan of the finishing-crimper.

In all these figures same letters refer to like parts.

In the figures, F F represent the sides of the frame-work, and B the cross-connection, which serves also for a bed or table for the mold-block and slide that carries the former. The sides F F are slotted to receive the tenons of the cross-head H. The cross-head H carries on its under side the finishing-crimper D. In the top of the table or bed-plate B is a slide, S, adapted to move backward and forward in a dovetail groove, and carrying on its face the horizontal plunger S'. Attached to the table B by bolts passing through the projecting arms f and said table is the mold-block M, in which is the mold O, adapted to receive the former S' and a heel-stiffener blank placed on the

forward end of said former. Attached to the cross-head H by hinge-connections are the toggles T. Of the other ends of these toggles, two are attached by hinge-connections e to the table B and two to the sliding plate S by hinge-connections e'. The two toggles hinged to the table B are cushioned, as shown at r in Fig. 3. The cross-head H is operated by the connection-rod L, which is eccentrically connected with gearing in such way as to impart to it a reciprocating motion. The upward and downward motion of the cross-head H and toggles T give a reciprocating horizontal motion to the slide S, which is regulated so as to carry the former S' into the mold O in its forward motion and to withdraw it from said mold in its backward motion.

In connection with the mold O, the horizontal former S', and the vertical plunger P, various devices have been employed to turn over and form the flanged part of the heel-stiffener. None of these devices has proved entirely satisfactory. An illustration of attempts of this kind may be seen in patents granted to Elbridge S. Mansill, November 14, 1882, Nos. 267,438 and 267,439, of which machine my invention is an improvement.

To turn the flanged part of the heel-blank accurately and uniformly, I make use of the following improved method: At or near the open end of the mold O, I attach to the sides of the mold-block M a plate or crimper, n, extending over and across the mold, as shown in Fig. 2. The crimper may be made adjustable by having the attaching-bolts run in slots t in the extended parts P of said plate n. I do not confine myself to any particular form or shape of the crimper-plate n. The essential feature of my invention is a crimper-plate placed above the mold, and under which the former, with the blank on the end thereof, must pass as it enters the mold.

The operation of this part of my device is as follows: The former S' being withdrawn from the mold, as seen in Fig. 2, the blank is placed in front of it and between it and the mold. As much of the blank as is desired to turn over to form the flange of the stiffener extends above the face of the former S'. The face

of the former is nearly level with the face of the mold-block, and consequently with the under surface of the crimper *n*. When the cross-head *H* descends, the slide *S*, carrying the former *S'*, with the blank placed as just described, is drawn forward into the mold, passing under the crimper *n*. As the blank passes under the crimper *n* the part thereof which projects above the face of the former is turned 10 over and down upon the face of the former. The former continues to enter the mold until the blank is firmly pressed between the end of the former and the inner end of the mold. At the same time the finishing-crimper *D* descends 15 upon the turned edge or flange of the blank and firmly compresses it between the face of the former and the face of the finishing-crimper. The former is then, by the upward motion of the cross-head and toggles, withdrawn 20 from the mold, and the blank, duly formed into a stiffener, may be taken out. It is of advantage to firmly press the sides of the stiffener and to give them a more solid texture and a smooth polished surface. This 25 I accomplish by making the mold *O* considerably longer than the length of the sides of the stiffener-blank when bent around the end of the former. The sides of the stiffener are thus pressed between the former and the sides of the mold as it is drawn into the mold. The 30 continued movement of the stiffener pressed against the sides of the mold tends to force

the particles more firmly together, and by the friction between the side of the blank and the sides of the mold the outer surface of the sides 35 of the stiffener is polished.

I disclaim the combination, with a die or mold and a series of pivoted crimping-levers and vertical plunger, of a longitudinal plunger and operating mechanism, as described 40 and claimed in patent to Elbridge S. Mansill, November 14, 1882, No. 267,438.

Having thus described my invention and its use, what I claim, and desire to secure by Letters Patent of the United States, is—

The combination, in a machine for forming heel-stiffener blanks, with the fixed block *M*, having mold or female die *O* and flange-turning plate *n*, sliding plate *S*, carrying male die *S'*, and suitable machinery for imparting a reciprocating movement to slide *S*, of the finishing-crimper *D*, attached to the cross-head *H*, and having its lower end adapted to enter the die *O* behind the flange-turning crimper *n*, all substantially as and for the purposes hereinbefore set forth.

In testimony that I claim the foregoing as my own I affix my signature in presence of two witnesses.

EUGENE H. TAYLOR.
